UNITED STATES PATENT OFFICE

2,636,480

REVERSIBLE FLUID MOTOR

Lester J. Becker, Alexandria, Va.

Application April 9, 1951, Serial No. 220,058

3 Claims. (Cl. 121—85)

1

This invention relates to fluid engines, and particularly to a rotary fluid-operated reversible motor or pump.

Hydraulic motors of the type herein described are useful especially when low speed, high torque driving means are required. An illustration of an apparatus which requires such a motor is the gun positioning mechanism of the present-day warship. Guns on a warship are usually movable through a substantial arc so they may be trained upon targets at varying azimuth from the ship. The guns are usually heavy and cumbersome so that a very high torque is required to move them, and they must be moved at a relatively slow speed to the particular azimuth at which they are to be fired, without hunting, and there be held positively against rotation. The apparatus for rotating the gun must be operable to move it in either direction without any delay, so that the gun need move only through the smallest possible arc within the shortest possible time to reach its desired azimuth. The motor of the present invention is particularly adapted for such requirements, since it furnishes high torque at a relatively low speed and it is possible to reverse the motor's direction of rotation without undue delay.

It has been previously proposed to provide fluid motors in which fluid under pressure is supplied to a plurality of chambers to move vanes carried by a rotor and extending into the chambers, successively past each chamber. However, in such motors the fluid under pressure, in addition to providing a torque for movement of the pistons and their associated rotor, exerted an inward pressure on the vanes tending to move them away from the walls of the fluid chambers so that the fluid within the chambers escaped around the vanes. To avoid the loss in efficiency caused by this action, it was proposed also to supply fluid under pressure to the inner ends of the vanes, so that the inward force on the outer ends of the vanes would be balanced by an outward force on the inner ends of the vanes. With this additional feature, the motor was efficient and practical, but only for rotation in one direction.

The object of the present invention is to provide a fluid motor which is simpler in design and less expensive in cost than earlier fluid motors of the type referred to above and which is also reversible in direction with a minimum of delay and effort. The apparatus herein described includes a rotor carrying vanes whose outer ends project into operating chambers formed between

2

a stator and the rotor. Supply of fluid to one end of each of the operating chambers and removal of fluid from the other end causes rotation of the rotor in one direction through the torque exerted on the vanes in that direction. To rotate the rotor in the opposite direction, the fluid is supplied to the end of each of the operating chambers which was previously the exhaust end and removed from the end which was previously the supply end.

In order to prevent the fluid in the operating chambers from forcing the vanes radially inwardly, the fluid supplied to the operating chambers is also transmitted to fluid chambers which communicate with the inner ends of the vanes. Thus, the inward force on the vanes is balanced by the outward force exerted on the vanes by the fluid from these last-mentioned fluid chambers. In order that this balancing of forces will always be effective on the vanes, no matter in which direction the rotor is rotating, both ends of each of the operating chambers must be connected to the fluid chambers. However, it is necessary at the same time to prevent fluid from passing through the fluid chambers to the ends of the operating chambers from which fluid is being exhausted, in order to prevent interference with the rotary movement of the rotor and decrease of the torque causing that movement.

The present invention provides a novel valve apparatus automatically operated by the fluid itself for isolating the exhaust ends of the operating chambers from the inlet ends, in both directions of rotation of the rotor.

In addition, the present invention provides a novel means for preventing fluid from passing from one operating chamber to another along the periphery of the rotor.

Though the fluid motor of the present invention is particularly adaptable to gun-positioning apparatus, it is capable of many varied uses. For instance, the motor may be used as the driving means for a land vehicle. To make it possible to steer the vehicle to which the motor is attached, means may be provided to allow movement of the motor about one of its axes.

An embodiment of the invention will be described in conjunction with the attached drawings, but it is to be understood that the invention is not limited to the specific embodiment herein disclosed but only by the subjoined claims.

In the drawings:

Fig. 1 is a sectional view through a preferred embodiment of the fluid motor of the invention, and

Fig. 2 is a sectional view taken along line 2—2 of Fig. 1.

The engine of the invention has a rotor 1 mounted on a rotatable shaft 2 concentric with an annular stator 3. Bearing plates 4 and 5 on opposite sides of the stator support the stator and form bearings for the shaft. The shaft terminates at one of its ends within a bearing box 6 on one side of the engine where it is rotatably supported, and at the opposite side of the engine the shaft passes through another bearing box 7 in which it is likewise rotatably supported.

A plurality of radial slots 8 extend axially of the rotor 1 from the outer periphery of the rotor radially to points adjacent the inner periphery thereof. Within each of these slots a vane or piston 9 of less length than the radial extent of the slots 8 is positioned for radial movement. Each of the vanes 9 is formed of two mating sections 10 and 11. Each of the sections 10 and 11 has a slot in its inner surface which forms one-half of a chamber 12 within the vane. Each of the sections 10 has a key 10a radially outward of its slot and a keyway 10b radially inward of its slot. Key 10a and keyway 10b of each of the sections 10 mate with keyway 11a and key 11b of the corresponding section 11, respectively. A spring 13 is mounted within each of the chambers 12 to urge the sections 10 and 11 away from each other against the opposing faces of the slot 8, for a purpose to be later explained. The springs are each normally of greater diameter than the chambers 12 within which they are positioned. Consequently, in assembly of the engine, the springs must be laterally compressed to permit the pistons to fit within their slots. The spring 13 then exerts a force on each of the mating sections 10 and 11 of each of the vanes 9 causing the outer sides of each of these sections to be firmly pressed against the adjacent face of the slot 8.

The outer periphery of the rotor 1 is substantially cylindrical in form, but the inner periphery of the stator is formed with a plurality of axially-extending surfaces 14 which are spaced from the rotor and separated from each other by axially-extending surfaces or lands 15 which are nearly contiguous to the rotor. As a result of this configuration of the inner periphery of the stator, a plurality of operating chambers 16, four in the illustrated embodiment, are provided between the stator and the rotor, the chambers 16 being bounded at their axial ends by the bearing plates 4 and 5.

A pair of annular grooves 17 and 17' are formed in the opposite end plates 4 and 5 of the engine. The radially inner surface of each of the grooves 17 and 17' forms a cam surface, 18 and 18', respectively, which is complementary to the inner periphery of the stator. The radial distance between the cam surfaces 18 and 18' and the inner periphery of the stator is the same over the entire 360° of these surfaces. The vanes 9 each have rollers 19 and 19' on their opposite axial ends which ride on these cam surfaces so that the vanes move alternately inwardly and outwardly as they move rotationally with the rotor.

The radial distance between the inner surface of each of the rollers 19 and 19' and the outer end of the corresponding vane 9 is substantially equal to the radial distance between the cam surfaces 18 and 18' and the inner periphery of the stator, so that the outer ends of the vanes 9 are always in contact with the inner periphery of the stator. It will be apparent that, though the rollers and

cam surfaces are preferable, other means, such as springs, could be employed to urge the vanes into contact with the inner periphery of the stator, and it will further be apparent that shoulders formed on the vanes could be used in place of the rollers to ride on the cam surfaces.

At one peripheral end of each of the operating chambers 16, a set of spaced passages 20 extends between the operating chamber and an annularly-shaped fluid manifold 21 in the stator. At the other peripheral end of each of the operating chambers, a second set of spaced passages 20' extends between the chamber and a second annularly-shaped fluid manifold 21' in the stator. Each of the sets of passages 20 and 20' is displaced a slight distance from the surface of land 15 to which it is adjacent at its place of communication with the operating chamber 16.

Fluid is supplied to or removed from the manifold 21 through a passage 22 which communicates with the outer side of the stator and is supplied to or removed from the manifold 21' through a corresponding passage 22' which also terminates at the outer side of the stator.

Each of the surfaces or lands 15 of the stator has an axially-extending preferably trapezoidal-shaped slot 23, within which a deformable bar or rod 24 of rubber or other appropriate material is positioned. When fluid under pressure enters one side of the slot 23, it exerts a transverse pressure on the bar or rod 24 which causes it to flatten out so that one of its sides is in fluid-tight contact with the inner side of the slot and the opposite side of the bar or rod is in fluid-tight contact with the outer periphery of the rotor. Consequently, the fluid cannot pass from one chamber 16 to another along the periphery of the rotor, even if the vanes 9 do not make good contact with the inner periphery of the stator.

To prevent fluid from passing from the operating chambers and the manifolds inward along the axial ends of the pistons a pair of sealing rings 25 and 25' are positioned between grooves in the end walls 4 and 5, respectively, and the adjacent surface of the rotor.

An axially-extending fluid chamber 26 is formed between the inner end of each of the slots 8 and the inner end of the corresponding vane 9 when the vane is in any position except its most inward position. All of the fluid chambers 26 communicate at one end with an annular chamber 27 and at the opposite end with a second annular chamber 27'. A surge chamber 28, communicating with the chamber 27, is provided in the end plate 4 to allow for expansion of fluid in the chambers 26, 26' and 27'.

The annular chamber 27 is connected by a passage 29 with a valve apparatus, generally indicated at 30, which comprises a fluid cylinder 31 within which a piston valve 32 of less length than the cylinder is positioned. One end 33 of the cylinder 31 is connected to the manifold 21, while the other end 33' thereof is connected to the manifold 21'. A pair of spaced passages 34 and 34' communicate at one end with the fluid cylinder 31 and at their other ends with the fluid passage 29.

The springs 13 above referred to exert forces on the mating sections 10 and 11 of each of the vanes 9 so that the outer sides of each of the vanes are in contact with the adjacent inner sides of the slots 8. Consequently, fluid cannot pass radially inward from the operating chambers 16 between the vanes and the slots, even if the mating sections of the vanes are not of the exact cor-

rect dimensions. Furthermore, the mating laterally-extending surfaces of the keyways 10b and 11a and the keys 10a and 11b are contiguous and prevent passage of fluid between the sections 10 and 11 of the vanes when the sections are pressed apart by the springs 13.

In the operation of this preferred embodiment of the invention as a motor, to cause rotation of the rotor and the shaft in the clockwise direction, fluid under pressure, preferably oil, is supplied through the passage 22 to the manifold 21. From the manifold 21, some of the fluid enters the end 33 of the fluid cylinder 31 and moves the piston valve 32 to the end 33' of the cylinder. The fluid then passes from the cylinder through the passage 34 and the passage 29 to the fluid chamber 27, from which it passes into the fluid chambers 26 and the fluid chamber 27'. The remainder of the fluid in the manifold 21 passes through the passages 20 into the operating chambers 16 where it exerts a torque on the vanes 9, forcing the vanes and the rotor which carries them in the clockwise direction. When a vane 9 is moving through one of the operating chambers 16, it is in its most outward position with its outer end in contact with a surface 14 of the stator. However, as the vane approaches one of the lands 15 between the operating chambers, it is moved inwardly until, when it is opposite the land 15, it is in its most inward position. As each of the vanes 9 is in turn passed through an operating chamber 16, the fluid in front of it is exhausted from the chamber through the passages 20' at the forward end of that chamber, the manifold 21' and the passage 22'.

The inward force exerted on the outer ends of the vanes 9 by the fluid in the operating chambers 16 is counterbalanced by the outward force exerted on the inner ends of the vanes 9 by the fluid in the fluid chambers 26, so that no unbalanced radial force is exerted on the vanes. This is particularly important should the cam surfaces not be of exactly the proper configuration and distance from the stator, since unbalanced pressure on the outer ends of the vanes would tend to move them inwardly and allow fluid to escape around the outer ends of the vanes. Supply of fluid under pressure to the chambers 26 furnishes an outward pressure for the vanes to balance the inward pressure and permit the cam surfaces and the centrifugal force of the rotor to keep the outer surfaces of the vanes against the inner periphery of the stator.

When the rotor and the shaft are to be rotated in the counter-clockwise direction, fluid under pressure is supplied through the passage 22' to the manifold 21'. A portion of the fluid in the manifold 21' enters the end 33' of the fluid cylinder 31 and moves the piston valve 32 to the end 33 of the cylinder. From the cylinder the fluid passes through the passage 34' and the conduit 29 to the fluid chambers 27, 26 and 27', as before, where it again exerts an outward force on the vanes.

The remainder of the fluid in the manifold 19' enters the operating chambers 16 through the passages 20' and there exerts a counter-clockwise torque on the vanes 9, causing the vanes and the rotor to rotate in a counter-clockwise direction. Fluid ahead of the vanes is exhausted from the operating chambers 16 through the passages 20 to the manifold 21 from which it passes through the passage 22 to an external collector.

If the engine is to be used as a pump, the shaft is rotated and fluid supplied through the pas-

sages 20 or the passages 20' to the operating chambers 16, depending upon whether the shaft is being rotated clockwise or counter-clockwise. The vanes 9 will force the fluid between them and the passages ahead of them in the operating chambers as they pass therethrough. The fluid urged out of the operating chambers is removed therefrom through the other set of passages 20 or 20', depending upon whether rotation of the rotor is in the clockwise or the counter-clockwise direction, and transmitted to the location at which the fluid is to be used or to appropriate storage means.

As stated above, it is contemplated that a motor of the type herein described could be utilized to drive the wheels of a land vehicle. In such case, the motors would be mounted on the axles of the vehicle with the shafts of the motors serving as stub shafts for the wheels of the vehicle. Diametrically opposite trunnions 35 and 35' are mounted on the stator of the motor to permit steering of the wheel of the vehicle through appropriate mechanism.

It will be apparent that a fluid-operated rotary engine has been described which is relatively simple and inexpensive to operate and which can be easily reversed in its direction of rotation.

The scope of the invention to which this description refers is defined in the following claims.

I claim:

1. A fluid engine comprising a shaft, a rotor mounted on said shaft and having a plurality of slots extending inwardly from the outer periphery of the rotor, vanes slidable in said slots, a stator surrounding said rotor and having an inner periphery including a plurality of surfaces spaced from each other and from the rotor and lands substantially contiguous to the rotor and separating said surfaces from each other to provide a plurality of operating chambers between the stator and the rotor, means for continuously urging the outer ends of said vanes into contact with the inner periphery of the stator, a first passageway system adapted selectively to supply fluid to and remove it from one end of each of said chambers, a second passageway system adapted selectively to remove fluid from and supply it to the other end of each of said chambers, whereby the direction of rotation of said rotor may be reversed, means including a fluid chamber in said stator for supplying fluid to the inner ends of said vanes, a valve chamber in said stator, a passage connecting said first passageway system to one end of said valve chamber, a passage connecting said second passageway system to the other end of said valve chamber, passage means connecting said valve chamber to said fluid chamber, and valve means in said valve chamber movable by fluid under pressure to said other end of said valve chamber when fluid is supplied to said first passageway system to allow communication between said first passageway system and said passage means and prevent communication between said second passageway system and said passage means, and movable by fluid under pressure to said one end of said valve chamber when fluid is supplied to said second passageway system to allow communication between said second passageway system and said passage means and prevent communication between said first passageway system and said passage means, whereby the inward pressure of the fluid in said operating chambers on said vanes is counter-balanced by the outward pressure of the fluid from the fluid chamber on said vanes.

2. A fluid engine comprising a shaft, a rotor mounted on said shaft and having a plurality of slots extending inwardly from the outer periphery of the rotor, each of said slots having a vane slideable therein, a stator surrounding said rotor and having its inner periphery including surfaces spaced from the rotor and from each other and lands substantially contiguous to the rotor and separating said surfaces from each other to provide a plurality of operating chambers between the stator and the rotor, means for continuously urging the outer ends of said vanes into contact with the inner periphery of the stator, a first set of fluid passages, one passage of said first set of fluid passages communicating with one peripheral end of each of said operating chambers, a second set of fluid passages, one passage of said second set of fluid passages communicating with the other peripheral end of each of said operating chambers, means adapted selectively to supply fluid to and remove fluid from said first set of fluid passages, means adapted selectively to remove fluid from and supply fluid to said second set of fluid passages, whereby supply of fluid to said first set of fluid passages and removal of fluid from said second set of fluid passages causes rotation of said rotor in one direction and supply of fluid to said second set of fluid passages and removal of fluid from said first set of fluid passages causes rotation of said rotor in the opposite direction, means including a fluid chamber in said stator for conducting fluid to the inner ends of said vanes, a fluid cylinder in said stator, a fluid passage connecting said first set of fluid passages to one end of said fluid cylinder, a second fluid passage connecting said second set of fluid passages to the other end of said fluid cylinder, a piston valve in said fluid cylinder movable by fluid under pressure to said other end of said valve chamber when fluid is supplied to said first passageway system and movable by fluid under pressure to said one end of said valve chamber when fluid is supplied to said second passageway system, and means for conducting fluid from said fluid cylinder to said fluid chamber in both positions of said piston valve, said fluid conducting means being isolated from said first set of fluid passages and connected with said second set of fluid passages when said pis-

ton valve is at said one end of said fluid cylinder and being isolated from said second set of fluid passages and connected with said first set of fluid passages when said piston valve is at said other end of said fluid cylinder, whereby the inward pressure of the fluid in said chambers on said vanes is counter-balanced by the outward pressure of the fluid from the fluid chamber on said vanes.

3. A fluid engine as defined in claim 2 in which each of said lands has an axially-extending slot therein, and a deformable bar in each of said land slots of smaller size than the slot, each of said slots in the lands being of such shape that fluid passing from an operating chamber between the periphery of the rotor and the land enters the slot and exerts pressure on said deformable bar causing the inner portion of said deformable bar to move radially inward and contact the outer periphery of the rotor and the outer portion of said deformable bar to contact the inner side of the slot in the land, so that the deformable bar seals the space between the periphery of the rotor and the inner side of the slot, said means for urging the outer ends of the vanes into contact with the inner periphery of the stator comprising a cam surface complementary with the inner periphery of the stator and having all points thereon substantially equi-distant from corresponding radial points on the inner periphery of the stator, and a roller carried by each of said vanes and riding on said cam surface.
